UNITED STATES PATENT OFFICE.

MORTON H. McTURK, OF PHILADELPHIA, PENNSYLVANIA.

COAL-SEPARATOR.

1,014,080.

Specification of Letters Patent. Patented Jan. 9, 1912.

Application filed August 30, 1910. Serial No. 579,727.

To all whom it may concern:

Be it known that I, MORTON H. McTURK, a citizen of the United States, residing at Philadelphia, county of Philadelphia, and State of Pennsylvania, have invented a new and useful Improvement in Coal-Separators, of which the following is a full, clear, and exact description, reference being had to the accompanying drawings, which form a part of this specification.

The object of my invention is to effect the separation of solids of different forms and specific gravities, and particularly the separation of coal from its accompaniment of slate, bone, etc., as in the mining and preparation of what is known as anthracite coal for the market. The customary method of accomplishing this is either by hand picking or by the use of palpitating jigs, which are both slow and uncertain in their results. In my invention the mixture is delivered into a hopper which leads to a tank of water in which a current is kept up about a vertical axis, producing a separation of the coal from the heavier ingredients, and delivering the coal and the separated material into different bins.

The preferred embodiment of an apparatus embodying my invention will be more readily understood from the following description in connection with the accompanying drawings, in which:

Figure 1 is a sectional elevation of the apparatus, and Fig. 2 is a sectional plan view on the lines 2—2 of Fig. 1.

A hopper *a* leads through a chute *b* to a circular tank *c*. Midway of its height this tank contains a division or diaphragm in the form of a circular helical runway *d*, having an inwardly and upwardly extending flare *e* terminating in a central chute or hopper *f*. Vanes or paddles *g* attached to a central vertical shaft *h* are caused to rotate by applying power to a pulley *i*. The helical runway *d* makes almost a complete circle and terminates in an opening *j* leading by a chute *k* directly into a boot or pocket *l*, into which dips one end of a conveyor *m*. The central hopper *f* opens at its bottom into a similar boot *n* into which dips

one end of a conveyor *o*. These conveyors *m* and *o* extend in an inclined direction up closed inclined passages *r* and *s* merging at their lower ends into the boots *l* and *n* respectively. The tank, the boots and conveyor passages, the hopper *f*, the chute *k* and the lower part of the chute *b*, which are intercommunicating as described, are all filled with water as shown in Fig. 1.

The operation is as follows: The mixture of coal, slate, etc., is fed into the hopper *a*, and deposited under water at the head of the helical runway *d*. The vanes *g* are made to rotate in the direction shown by the arrow, at a speed sufficient to keep a current of water constantly flowing in that direction around the interior of the tank, but not sufficient to produce churning. The combined action of this current of water, together with the pitch of the helical runway *d*, maintains a steady flow of coal mixture around the runway. The tendency of both the coal and slate is to go toward the center, but the upwardly and inwardly extending flare *e* offers too much resistance for the slate, which is of higher specific gravity, to pass over to the central opening, but does not offer sufficient resistance to prevent the coal from so passing over. The operation, therefore, is that the coal, in the course of the passage of the mixture around the runway, discharges itself from the heavier matter and falls through the central hopper *f* into the boot *n*, while the heavier constituent is carried around to the end of the runway *d* and is delivered through the opening *j* into the boot *l*. As fast as the coal is delivered into the boot *n*, the conveyor *o* carries it up out of the boot *n* and deposits it in a coal bin on one side of the divisional wall *p*, while the conveyor *m* carries the separated impurities up out of the boot *l* and deposits them separately from the coal on the other side of the divisional wall.

In the practical employment and operation of the invention, I find that with a tank four and one-half feet in diameter, and with an apparatus constructed on substantially the scale shown in the drawings, the apparatus will work efficiently if the shaft 95

be rotated at about 24 revolutions per minute. The feed of coal is preferably continuous, and it will, of course, be fed into the tank as rapidly as the rotating current of water will carry it around and separate it. The amount of coal that will be separated under the foregoing conditions will be about eight or ten tons per hour. The foregoing data, however, is merely given as an example of working conditions, and it will be understood that the invention is not limited to any particular working conditions.

Having now fully described my invention, what I claim and desire to protect by Letters

15 Patent is:

1. In a solids separator, the combination with a runway having an unobstructed inner edge and having an upper face extending upward and inward toward a central opening, of means to maintain above the runway a current of water in a direction corresponding to the downward lengthwise slant of the runway.

2. In a solids separator, the combination with a helical runway having an unobstructed inner edge and a part of whose upper face extends inward and upward, there being a centrally disposed outlet communicating with the inner higher rim of the runway, and a peripherally disposed outlet communicating with the lower end of the runway, and means to maintain a constant circular current of water above said runway in a direction corresponding to the downward lengthwise slant of the runway.

3. In a solids separator, the combination with a tank adapted to contain water and to receive the solids to be separated, of a runway, extending around the inner wall thereof, of, whose inner edge is at a substantially higher elevation than its outer edge at any transverse section substantially throughout the length of the runway, and means to maintain above the runway a current of water in a direction corresponding to the downward slant of the runway.

4. In a solids separator, the combination with a tank, of a helical runway extending around the inner wall thereof, having an unobstructed inner edge and having an upper face extending upward and inward toward a central opening, there being a second opening at the lower end of the runway, and means to maintain a constant circular current of water above the runway in a direction corresponding to the downward lengthwise slant of the runway.

5. In a solids separator, the combination with a tank adapted to contain water and to receive the solids to be separated, of a runway, extending around the inner wall thereof, having an unobstructed inner edge and having an upper face inclined upward to-

ward said edge, and means to maintain above the runway a circular current of water in a direction corresponding to the downward lengthwise slant of the runway.

6. In a solids separator, the combination with a tank, of a helical runway extending around the inner wall thereof, the outer part of the runway being, at different transverse sections thereof, substantially level while the inner part thereof extends upward and inward, and means to maintain above the runway a constant circular current of water in a direction corresponding to the downward lengthwise slant of the runway, there being a central discharge opening within the inner rim of the runway and a discharge opening at the lower end of the outer section of the runway.

7. In a solids separator, the combination with a tank adapted to receive the solids to be separated, of a helical runway in said tank having an inwardly and upwardly extending flared portion, there being a centrally disposed outlet for the lighter ingredients and an outlet at the lower end of said runway for the heavier ingredients, means for producing a circular flow of the water in the tank above the runway, and means for separately raising above the water level the heavier and the lighter ingredients discharged from said runway respectively into said outlets.

8. In a solids separator, the combination with a tank, to receive the solids to be separated, a helical runway extending around the inner wall of the tank, boots communicating respectively with the central space within the inner rim of the runway and with the lower end of the runway, inclined conveyer passages communicating respectively with said boots, and conveyers in said passages, the said intercommunicating tank, boots and conveyer passages adapted to contain water the upper level of which is substantially above the runway, and revoluble vanes above the runway.

9. In a solids separator, the combination with a tank to receive the solids to be separated, of a helical runway extending around the inner wall of the tank, the inner part of said runway extending upward toward its inner rim, revoluble vanes in the tank above runway, a pocket for the lighter constituents connected with the space within the inner rim of the runway, a pocket for the heavier constituents connected with lower end of the outer part of the runway, the said tank and pockets adapted to contain water submerging the runway and vanes, and means to convey the constituents delivered to said pockets above the level of the vanes.

10. In a solids separator, the combination

with a tank adapted to contain water, of means to receive the lighter ingredients located centrally of the tank, means to receive the heavier ingredients located at the inner 5 wall of the tank, and a runway, extending, from a point substantially above the second receiving means, spirally around the inner wall of the tank to the mouth of the second receiving means, the inner edge of said run-

way being unobstructed and communicating 10 with the first receiving means.

In testimony of which invention, I have hereunto set my hand, at Stockbridge, on this 25 day of August, 1910.

MORTON H. McTURK.
